MUSICAL INSTRUMENT

Henderson N. White, Euclid, Ohio, assignor to
 The H. N. White Company, Cleveland, Ohio, a
 corporation of Ohio

Application February 25, 1939, Serial No. 258,409

9 Claims. (Cl. 84—380)

This invention relates as indicated to musical instruments, but has reference more particularly to wind instruments, such as flutes and clarinets, especially to the bodies of such instruments and 5 to a method of making the same.

It has heretofore been proposed to make the bodies of wind instruments, such as clarinets and flutes, from tubes of an alloy such as nickel (German) silver. Such an alloy, while possessing 10 strength and the ability to be stamped and drawn into shape, has not been found to be entirely satisfactory from the standpoint of tonal qualities, resonance and playability.

I have found that the tonal qualities, resonance, 15 brilliancy and playability of such instruments may be greatly increased, without appreciable decrease in the strength of the body or the ability to stamp or punch holes therein, by the simple expedient of making a body, comprising a nickel-silver tube lined with a tube of relatively pure 20 silver, such as sterling silver.

Other objects and advantages of the invention will be apparent during the course of the following description.

25 In the accompanying drawing, forming a part of this specification, and in which like numerals are employed to designate like parts throughout the same:

Fig. 1 is a fragmentary cross-sectional view, 30 illustrating the first step in the manufacture of a clarinet or flute body in accordance with the invention;

Fig. 2 is a view similar to Fig. 1, but showing 35 the second step in the manufacture of the body; and

Fig. 3 is a fragmentary cross-sectional view of 40 the complete flute or clarinet body.

Referring more particularly to the drawing, the first step in the manufacture of the bell consists 45 in placing a tube 1, of sterling silver, on a mandrel 2 and then drawing the mandrel and tube through a die 3, which is similar to a wire drawing die, and as a result of which the tube 1 is considerably elongated and the walls thereof reduced in thickness to nearly the thickness desired in the final body.

The second operation consists in placing a tube 4, of nickel silver, on the tube 1 and mandrel 2, and in then drawing the assemblage of tubes and 50 mandrel through a die 5, similar to the die 3, and as a result of which, the tube 4 is considerably elongated and the wall thickness thereof appreciably reduced. In this operation, the tube 1 is also further elongated and reduced somewhat in 55 wall thickness, so that the tubes 1 and 4 are firmly

and intimately united to each other, forming in effect, a single tube.

Upon removal of the mandrel, the body of the instrument will appear as in Fig. 3, consisting of an outer wall 4, of nickel silver, of a thickness of approximately .028" and an inner wall or lining 1, of sterling silver, of a thickness of approximately .014". In other words, for best results, it has been found that the outer wall should be approximately twice the thickness of the inner 10 wall.

A flute or clarinet constructed in accordance with the foregoing description, has been found to have greater resonance and brilliancy of tone 15 than an instrument in which the body is formed wholly of nickel silver. Moreover, it is easier to play, being less difficult to blow for the production of tones of the same pitch. At the same time, the strength of the body is not appreciably 20 reduced, and the body can be easily punched or stamped for the various holes required in instruments of this type.

Although the instrument body has been described as preferably made of nickel silver and 25 sterling silver, good results have also been attained where the outer wall of the tube is made of other metals and alloys, as for example, brass. Moreover, the inner wall may be made of other 30 pure or elementary metals of relatively high density, as for example, gold and platinum, although the use of these metals, due to their high cost, is virtually out of consideration in the manufacture of musical instruments.

It is to be understood that the forms of my 35 invention, herewith shown and described, are to be taken as preferred examples of the same and that various changes in the shape, size and arrangement of parts may be resorted to, without departing from the spirit of my invention, or the 40 scope of the subjoined claims.

Having thus described my invention, I claim:

1. A tubular musical instrument body comprising 45 an outer wall of drawn metal other than silver and an inner wall of drawn silver.

2. A tubular musical instrument body comprising 50 an outer wall of drawn nickel silver and an inner wall of drawn silver.

3. A tubular musical instrument body comprising 55 a wall of drawn nickel silver and a lining of drawn silver, said wall being approximately twice as thick as said lining.

4. A tubular musical instrument body comprising 60 a wall of drawn nickel silver about .028" thick and a lining of drawn silver about .014" thick.

5. A tubular musical instrument body comprising an outer drawn wall of an alloy metal and an inner drawn wall of an elementary metal of relatively high density, said walls being in pressed fit contact with each other throughout their length.
6. A tubular musical instrument body comprising an outer wall of drawn nickel silver and an inner wall of drawn gold.
7. A tubular musical instrument body comprising an outer wall of drawn nickel silver and an inner wall of drawn platinum.

8. A tubular musical instrument body comprising an outer wall of drawn nickel silver and an inner wall of drawn silver, said walls being in contiguity with each other throughout their length.

9. A tubular musical instrument body comprising an outer wall of drawn nickel silver and an inner wall of drawn silver, said walls being in pressed fit contact with each other throughout their length.

HENDERSON N. WHITE.
